UNITED STATES PATENT OFFICE.

HANS RIEGGER, OF BERLIN-PANKOW, GERMANY, ASSIGNOR TO SIEMENS & HALSKE AKTIENGESELLSCHAFT, OF SIEMENSSTADT, NEAR BERLIN, GERMANY, A CORPORATION OF GERMANY.

ELECTRICAL CHANGE-OVER APPARATUS.

Application filed August 24, 1922. Serial No. 584,084.

To all whom it may concern:

Be it known that I, HANS RIEGGER, a citizen of the German Empire, residing at Berlin-Pankow, Germany, have invented 5 certain new and useful Improvements in or Relating to Electrical Change-Over Apparatus, of which the following is a specification.

My invention relates to electrical change- 10 over apparatus for alternating currents and is preferably used for submarine signalling purposes.

When receiving sounds under water it is 15 frequently important to determine which one of various receiving devices is excited the strongest by the incoming sound waves, as a conclusion as to the point of origin of the sound waves can be drawn from this determination. In order that such determination may be possible even in the case of 20 very weak incoming energy it is necessary to listen to the sounds as received at the different receiving devices in quick succession with one and the same telephone receiver. For this purpose change-over switches, slip rings or the like have hitherto been employed but such devices are unsatisfactory, as the transitory variations of 25 resistance which arise in them usually of themselves set up loud noises in the telephone or at least interfere greatly with the sounds being received.

The object of my invention is to effect 30 the necessary change-over operation without the employment of any physical contacting devices such as slip rings, change-over switches or the like in the circuit.

According to my invention a rotatable 35 system is provided which carries two electrically connected transformer coils, the axis of which are disaligned relatively to each other. The axis of one of these coils lies in the axis of rotation of the system and this 40 coil is permanently in mutual inductive relationship with a third coil. The other of the two coils carried by the rotatable system describes a circle when the system is rotated 45 passing successively into mutual inductive relationship with a series of additional 50 transformer coils.

In order that the said invention may be 55 clearly understood and readily carried into effect the same will now be described more

fully with reference to the accompanying 55 drawings in which: Figure 1 is a side elevation of one constructional form of the invention, Figure 2 is a front elevation of another constructional form.

Referring to Fig. 1 two receiving devices 60 for submarine signals are designated 1 and 2 one of which may be placed on the port side and the other on the starboard side of a ship. The currents produced in the receiver 1 flow through the stationary coil 65 3, and those produced in the receiver 2 through the stationary coil 4. The rotatable system consists of a shaft 5 on which a coil 6 and a carrier arm 7 are mounted. On this arm is mounted a coil 8, which is 70 electrically connected with the coil 6 by means of the conductors 11. The coil 6, which rotates with the shaft 5 about its own axis, is in permanent mutual inductive 75 relationship with the coil 9, which is in electrical connection with the earpiece 10. In the position of the apparatus indicated in full lines the alternating currents produced in the receiver 1 are reproduced in the earpiece 10 by inductive action between coils 3 and 8, and 6 and 9 respectively. If the shaft 5 be rotated through 180° the coil 8 is brought into the position indicated in dotted lines, that is to say into mutual inductive 80 relationship with the coil 4. In this case the currents produced in the receiver 2 are reproduced in the earpiece 10. The change-over is thus effected without any 85 of the circuits being broken and without the employment of any contact spring, mercury or other contacts.

In addition to the coils 3 and 4 other coils 90 may be provided at the same distance from the shaft 5, with which coils the coil 8 may be brought into mutual inductive relation 95 by suitable angular displacement of the rotatable system.

An apparatus of this kind is shown in Fig. 2. There are three stationary coils 100 with windings 21, 22, 23 surrounding cores 24, 25, 26 respectively. These coils and cores are as will be seen from the drawing of elongated cross-section with the object of allowing the shaft 5 to rotate uninterrupted. During one portion of a revolution the coil 8 which is fixed to the shaft 5 105 by the arm 7 in the same way as shown by

Fig. 1, will be in mutual inductive relationship for an appreciable time with each of the three coils 21, 22, 23. The coils are electrically connected with the receiving devices 5 27, 28, 29 respectively. The incoming sound waves will be heard successively in the telephone 10.

Though I have described my invention as used for submarine signalling purposes 10 it is obviously not limited to this way of being used but will prove useful in numerous other connections where the employment of switches, slip rings or liquid contacts would involve disadvantages.

15 I claim:

1. Change-over apparatus for alternating currents, comprising in combination a rotatable part, a transformer coil carried by the rotatable part the axis of the coil being in

alignment with the axis of the rotatable 20 part, a second transformer coil carried by the rotatable part and electrically connected to the other coil the axes of the coils being disaligned relatively to each other, a third transformer coil arranged stationary and 25 placed in mutual inductive relationship with the first coil, and other stationary transformer coils placed along the path of the second transformer coil when rotated.

2. In change-over apparatus for alternating currents the combination with the elements claimed in claim 1 of an indicating device electrically connected to the third transformer coil and of submarine receivers 30 electrically connected to the other stationary 35 transformer coils.

In testimony whereof I affix my signature.
HANS RIEGGER.
